UNITED STATES PATENT OFFICE.

CARLETON F. SWASEY, OF NEW CANAAN, CONNECTICUT, ASSIGNOR TO WESTERN ELECTRIC COMPANY, INCORPORATED, OF NEW YORK, N. Y., A CORPORATION OF NEW YORK.

CASING AND SUPPORT FOR ELECTRICAL APPARATUS.

Application filed May 11, 1922. Serial No. 560,069.

This invention relates to casings and supports for electrical apparatus and more particularly to a means for mounting relays.

It is an object of the invention to mount a relay or other piece of apparatus upon a plate which has attached to one side a number of jacks for receiving corresponding plugs on a rack, and has on its other side a support upon which the relay or apparatus rests.

Another object of the invention is to improve a cover, for apparatus so that it may be snapped over a support to completely house the apparatus, and to protect it from dirt and dust.

More specifically, the invention relates to a means for mounting apparatus on a rack, this means comprising a mounting plate or frame provided with a plurality of jacks or terminals to receive plugs which are provided on the mounted apparatus, this plate having attached thereto a three-sided receptacle upon which the weight of the apparatus rests. This receptacle is so shaped that the apparatus fits snugly within the same and its sides are furthermore cut away leaving the adjusting means for the apparatus readily accessible. A cover is provided with retaining springs which are snapped over studs integral with the sides of the receptacle and thus securely held in place.

In the drawings, Fig. 1 shows a preferred embodiment of the apparatus mounting partly in section, the improved cover being withdrawn as in the apparatus itself, to disclose the details of these parts, while Fig. 2 is a plan view of the apparatus as it appears when housed within the receptacle and cover, and Fig. 3 is an end view of the apparatus and the housing.

Referring to the drawings in detail, a mounting plate 1 has securely attached to its one face a U-shaped terminal supporting connecting block 2 upon which is mounted a plurality of terminals or jacks 3 which are accessible from the other side of the mounting plate 1 through an opening 4 provided for this purpose. A three-sided supporting receptacle 5 is attached to the opposite face of the mounting plate 1 and projects perpendicularly therefrom. This receptacle 5 supports the weight of a relay 6 which is shown as of the type disclosed in Patent No. 1,523,423, granted to

Joseph F. D. Hoge January 20, 1925; but may be any other apparatus, the invention not being limited to any specific device. The supporting receptacle has its sides cut away as shown in the drawing at 7 in order that the relay adjusting means 8 may be readily accessible while the relay is mounted on the rack. The vertical sides of the receptacle 5 are also bulged outwardly at 9 where they join the horizontal portion of the support, this construction conforming with the relay base 17 which is slightly wider than the relay 6 itself. A plurality of plugs 10 secured to the relay base 17 are provided for insertion into the jacks 3 secured to the mounting plate or frame 1, and cooperate therewith to hold the relay in place while on the receptacle 5. The plugs 10 may serve as terminals for the windings and contacts of the relay and by contacting with the jacks 3 may connect the relay into any suitable circuit with which the jacks may be associated.

A metallic cover 11 having a projecting handle or flange 12 is so constructed as to permit it to slide over the top of the supporting receptacle 5. Metal strips 13 provided with U-shaped flanges 14 are attached to the interior of the sides of the cover 11. Leaf springs 15 are riveted to the flanges 14 of the metal strips 13 and are therefore similarly spaced from the interior surface of the cover 11. When the cover 11 is slid over the supporting receptacle 5, the flanges 14 rest upon the sides of the receptacle, whereas the leaf springs 15 ride up over studs 16 on the receptacle 5 and snap in place beyond these studs, thereby securely holding the cover 11 in place.

The bulged formation of the receptacle 5 permits the sides of the cover 11 to align themselves with the wide support, so that the entire housing when assembled, has smooth uniform sides and therefore presents a neat and compact appearance.

What is claimed is:

1. An apparatus mounting comprising a plate having mounted thereon a trough-like receptacle for supporting apparatus, said receptacle being provided with studs on the interior surface of its sides and an open-ended cover adapted to slide over said receptacle, said cover being provided with flanges and internally mounted resilient members cooperating with the said studs on said re-

100

110

ceptacle for securely holding said cover in place, said elements comprising the receptacle cover and fastening means being so constructed and arranged that when the cover is placed in position it will exert no strain on the apparatus placed in said receptacle.

2. A mounting for delicately adjusted electrical apparatus, comprising a mounting plate, an open ended channel shaped sup-

port having upwardly extending sides, said support being mounted on said plate, a closed ended channel shaped cover having downwardly extending sides adapted to overlap the upwardly extending sides of said support and fastening means for securing said cover to said support. 15

In witness whereof, I hereunto subscribe my name this 3rd day of May, A. D. 1922.

CARLETON F. SWASEY.
